Des. 207,335
Patented Apr. 4, 1967

207,335

COFFEE PERCOLATOR

Stephen H. Kaminski, Warren, Mich., assignor to Sun-beam Corporation, Chicago, Ill., a corporation of Illinois

Filed Sept. 8, 1966, Ser. No. 3,768

Term of patent 14 years

(Cl. D44—26)

Fig. 3.

Fig. 4.

Fig. 5.

FIG. 1 is a perspective view of a coffee percolator showing the novel design;

FIG. 2 is a side elevational view of the percolator;

FIG. 3 is a front elevation view of the percolator;

FIG. 4 is a rear elevation view of the percolator; and FIG. 5 is a top plan view of the percolator.

The essential features of the design are shown in solid lines.

I claim:

The ornamental design for a coffee percolator, as shown and described.
